UNITED STATES PATENT OFFICE.

GEORGE E. BAKER, OF SCIPIOVILLE, NEW YORK.

TAKE-UP DEVICE FOR BEARINGS.

Application filed December 28, 1923. Serial No. 683,187.

This invention has for its object an automatically adjustable bearing for shafts, and particularly means for adjusting the bearing, between the connecting rod and the 5 crank shaft of an internal combustion engine, which means is particularly simple and compact in construction, readily applied and highly efficient and durable in use.

The invention consists in the novel features and in the combinations and constructions hereinafter set forth and claimed.

In describing this invention reference is had to the accompanying drawings in which like characters designate corresponding 15 parts in all the views.

Figure 1 is an inverted plan view of a bearing embodying my invention, contiguous parts of a crank shaft being also shown.

Figure 2 is a transverse sectional view 20 partly in elevation taken on line 2—2, Fig. 1.

Figure 3 is an enlarged fragmentary sectional view similar to Fig. 2, of a preferred construction of the bolt and nut with the cams on the neck of the nut.

Figures 4 and 5 are respectively a plan view and an edge view of one of the cams.

This bearing comprises a box, comprising opposing sections, means for clamping the sections together, including pins extending 30 through the sections on opposite sides of the shaft and having shoulders engaging the outer face of one section and shoulders opposed to the outer face of the other section, and cams pivotally mounted concentric with 35 the pins between the latter shoulders and the opposing face of the contiguous section, said cams being constructed to move on their pivots, and in so doing thrust in one direction directly against the bearing section, and in the other direction against such shoulders, and thus clamp the sections toward each 40 other and take up looseness or wear.

I have here illustrated my invention as applied to a crank shaft of an internal combustion engine, and particularly the crank shaft of a Ford engine.

1 designates the crank shaft, 2 the crank thereof, 3 the crank pin. 4 and 5 are the 50 sections of the bearing box, one of such sections as the section 5, being integral with the connecting rod 6.

7 is the babbitt bearing on the shaft 3, and held in position by the bearing sections 4 and 5, the babbitt bearing being formed as 55 usual of two sections located respectively in the sections 4 and 5.

8 are the pins extending through the sections 4 and 5, on opposite sides of the shaft or crank pin 3 and each pin having a shoulder 9 at one end thrusting against one section, as 5, and a shoulder 10 at its other end opposite to the outer face of the section 4.

These pins 8 are usually bolts, and the shoulders 9 are the heads of the bolts and the shoulders 10 are nuts, threaded on the bolts. 60 In the usual construction such nuts 10 are tightened against the section 4, and are locked in position and when it is desired to tighten the bearing the nuts are unlocked and tightened, and again locked. 70

Automatic means or cams have been devised for automatically tightening the bearings, but my automatic means is radically different than those heretofore devised.

My means for tightening the bearings, 75 comprises cams pivoted on the pins or bolts 8 between the shoulders thereon, and one of the sections 4 or 5, preferably between the nuts 10 and the section 4, these cams having pivotal movement about the bolts 8, and having cam faces arranged to thrust outwardly on the nuts 10 and inwardly on the section 4, during such pivotal movement. 80 As here shown, there are two cams mounted on each bolt 8. 85

11 and 12 designate the cams mounted on each bolt 8, each cam being here shown as in the form of a flat ring or washer, having a laterally extending arm 13, the rings or washers, each having oppositely inclined 90 cam faces 14 and 15, which engage inclined plane fashion, complementary faces 14 and 15, on the other ring or washer. The ring or washer 11 is arranged with its flat face 95 against the bearing section 4 and the washer 12 is arranged with its flat face against the bolt 10 so that, the inclined faces of the cams coact inclined plane fashion on each other during pivotal movement of the cams.

The means for automatically moving the 100 cams on their pivots, comprises springs 16, one spring 16 being connected to the arms 13, of the cams 11, and the other spring 16 connecting the arms 13 to the cams 12, so that the springs tend to move the cams on 105 their pivots to cause their inclined plane faces to ride up each other, and hence, to cause the cams to thrust outwardly on the bolt 10, and inwardly on the section 4, and take up any looseness developed in the 110 bearing.

In Ford cars there is not enough space

to use the bolts and nuts on the crank for number 4 cylinders, as such bolts are liable to strike the oil pans or bottom of the crank case; and hence, in order to shorten the bolt and use a nut having a sufficient number of threads the head of the nut is made thinner and the nut formed with a neck 17 which extends through the cams, that is, cams are mounted on the neck 17, see Fig. 3.

19 The cams 11 and 12, are preferably so arranged that in initially tightening the nuts, the lowermost cam is pulled backwardly as far as possible, against the tension of the spring 16 and held, and when the nut is tightened, it turns in such direction as to turn the other cam 12 backwardly outwardly to its starting position against the influence of the spring 16. Such cams are readily applied to the bearings and are not affected by the 20 throw or centrifugal force of the crank, and further efficiently take up the wear as it develops in the bearing.

What I claim is:

1. In a bearing structure the combination 25 of a shaft, a bearing box comprising opposite sections mounted on the shaft, a pin extending through the sections, shoulders at opposite ends of the pin, cam means pivoted on the pin between one of the shoulders and the contiguous bearing section, and being 30 arranged to push such section toward the other section and thrust the pin endwise, the cam means having a laterally extending arm and a spring connected to said arm 35 tending to turn the cam.

2. In a bearing structure, the combination 40 of a shaft, a bearing box, comprising opposite sections mounted on the shaft, pins extending through the section on opposite sides of the shaft, pairs of cams pivoted on

each pin, one cam lying on the other, the cams having inclined faces on their opposing sides arranged to thrust the cams in the opposite directions, a shoulder on each pin thrusting against one of the cams, said 45 cams having laterally extending arms and springs connected to said arms and tending to turn the cams.

3. A take-up bearing device, comprising a pin for holding two bearing sections together, a shoulder on the pin, a pair of cams pivoted on the pin between the shoulder and one of the bearing sections, the cams having opposing inclined surfaces engaged with each other and laterally extending 55 arms, and springs connected to said arms.

4. In a bearing structure, the combination of a shaft, a bearing box mounted on the shaft, comprising opposing sections, bolts extending through the sections on opposite 60 sides of the shaft, nuts threading on the bolts, a pair of pivoted cams mounted concentric with each bolt between the nut and the contiguous bearing section, said cams having coacting inclined faces on their opposing sides, and having arms extending laterally in opposite directions, the inclined faces being arranged to thrust the cams in opposite directions along the bolt against the nut and the contiguous bearing section, 70 upon pivotal movement of such cams, and springs connecting the laterally extending arms of the cams on one side of the shaft with the cams on the other side of the shaft.

In testimony whereof, I have hereunto signed my name, at Merrifield, in the county of Cayuga and in the State of New York, this 15th day of Nov., 1923.

GEORGE E. BAKER.
